UNITED STATES PATENT OFFICE.

JOSEPH HOWE, JR., OF KANSAS CITY, MISSOURI.

DESIGN FOR A LAMP.

59,845.

Specification for Design.

Patented Nov. 29, 1921.

Application filed October 1, 1920. Serial No. 414,123. Term of patent 3½ years.

To all whom it may concern:

Be it known that I, JOSEPH HOWE, Jr., a citizen of the United States, residing at Kansas City, in the county of Jackson and State of Missouri, have invented a new, original, and ornamental Design for a Lamp, of which the following is a specification, reference being had to the accompanying drawing, forming part thereof.

In the drawings,

Fig. 2 is a side perspective view of the same.

I claim:

The ornamental design for a lamp as shown.

JOSEPH HOWE, JR.
